SLICER HAVING A TENSIONED WIRE CUTTING ELEMENT

Alfred Richard Deedman and William G. Lambrou,
Canton, Ohio

Application March 23, 1954, Serial No. 418,079

3 Claims. (Cl. 30—114)

This invention comprises novel and useful improvements in a slicer and more specifically pertains to an apparatus for slicing cakes or pies into segments in an improved manner.

The principal object of this invention is to provide a slicer for cakes and pies which shall effect a more precise and clean severing and dividing of cakes or pies into segments of selected size.

A further object of the invention is to provide an apparatus in accordance with the preceding object wherein the cutting element shall comprise a tensioned wire.

A still further object of the invention is to provide an apparatus in conformity with the above mentioned objects wherein the article to be sliced shall be carried upon a rotatable table together with indexing means for positioning the table in predetermined positions with respect to the slicing element.

A still further important object of the invention is to provide a slicing device in accordance with the above mentioned objects which shall include an improved means for guiding the severing element of the device and for applying adjustable tension thereto.

A final important object of the invention is to provide a severing device in accordance with the preceding objects together with an improved covering for the same.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary top plan view, parts being broken away, of an apparatus in accordance with the principles of this invention;

Figure 2 is a vertical transverse sectional view taken substantially upon the plane indicated by the section line 2—2 of Figure 1, the severing means being shown in its vertical position in full lines and in an intermediate position in dotted lines therein;

Figure 3 is a fragmentary detail view taken upon an enlarged scale substantially upon the plane indicated by the section line 3—3 of Figure 2;

Figure 4 is a detail view taken upon an enlarged scale substantially upon the plane indicated by the section line 4—4 of Figure 2 and showing the manner in which the severing element of the device is resiliently attached to the base of the device;

Figure 5 is a perspective view of the device showing the manner in which an article is sliced thereby; and

Figure 6 is a perspective view of the cover for enclosing the device when the latter is not in use.

Referring now more specifically to the accompanying drawings, wherein like numerals designate similar parts throughout the various views, it will be seen that the device includes a flat plate-like base 10 which is preferably of circular shape, and which is provided with a central drum-shaped raised flange 12 having a top wall

2

14. This top wall 14 together with its supporting flanged rim 12 constitutes a table support upon which is rotatably received a table indicated generally by the numeral 16 and which includes the circular top wall 18 and an annular skirt or rim 20. The table is adapted to be rotatably received upon and embrace the table support, with the top wall 18 resting upon the top wall 14 of the support and with the rim 20 slidably embracing and being guidingly mounted upon the table support wall 12, as shown clearly in Figure 2.

The table 16 constitutes a support for an article, such as a cake 22, which is to be sliced or severed by the apparatus, and an indexing means is provided for positioning the table in rotationally adjusted selected positions. Thus, the wall 12 of the table support is provided with an inwardly extending tubular boss 24 in which is secured in any suitable manner, a cup-shaped sleeve 26 which is provided with a detent ball 28 yieldingly urged outwardly of the sleeve, as by a compression spring 30. The rim 20 of the table is provided with a plurality of outwardly directed protuberances forming pockets 32, see also Figure 1, which are adapted to selectively register with the detent 28 in rotationally adjusted positions of the table 16. Thus, any suitable number of the pockets 32 being provided, the table may be yieldingly maintained by the detent ball 28 in various selected rotationally adjusted positions with respect to the base and the table support.

An arcuate guide 34 in the form of a semi-circular metallic band is mounted upon and rigidly secured to the base 10 as by flanges 36 at the ends of the guide which are welded or otherwise firmly connected with the base, the band being disposed diametrically on the circular base and extending above the table and the table support, as will be best apparent from Figure 5. The guide 34 is provided with an arcuate slot 38 which extends from one end of the guide at the horizontal level of the top of the table support to a position directly above the center of the table and of the base.

The severing element of the device consists of a tensioned wire 40, having one end anchored below the center of the table support and having its other end fixed to a handle which is slidably retained in the guide 34.

Referring now to Figure 4, it will be apparent that the central portion of the top wall 14 of the base is provided with a central aperture 42, and the central portion of the rotatable table 16 in its top wall 18 is also provided with an aperture 44 for registering with the aperture 42. The cutting wire 40 extends through these apertures and has its lower end secured to a pivot or anchor pin 46 which is loosely received but is retained in aligned apertures 48 in a pair of brackets 50 which depend from the wall 14. The apertures 48 are vertically elongated to permit a limited vertical movement of the anchor pin 46 and consequently of the end of the cutting wire 40 secured thereto. A compression spring 52 surrounding the wire 40 has its opposite ends abutting against the top wall 14 and the pin 46 to yieldingly urge the latter downwardly towards the lower end of the elongated slots 48, thereby applying a tension to the cutting wire 40 but being sufficiently yieldable to permit upward movement of this wire as set forth hereinafter.

As shown best in Figure 2, the upper end of this wire is secured to a transverse supporting pin 54 between a pair of bifurcations 56 formed on the lower end of a bolt-like member 58. The latter forms part of an actuating handle, indicated generally by the numeral 60 by which the wire is pivoted about its lower end. The handle further includes an outer sleeve member 62 in which the member 58 is received, the upper end of the pin 58 being externally threaded, as at 64, to receive a tensioning nut 66 thereon, which nut, in turn, has

fixedly secured thereto a sleeve 68 constituting the means for rotating the nut. The lower end of the nut 66 is adapted to abut against the sleeve 62 whereby upon rotation of the sleeve, the member 58 together with the wire 40 attached thereto will be moved upwardly to tension the wire. The sleeve 62 has a diametrically slotted lower end, as at 70, which slots receive the ends of the transverse pin 54. This arrangement permits this pin to move vertically of the sleeve by means of the slot 70, but prevents relative rotation of the member 58 with respect to the sleeve. Thus, upon rotating the cap 68, the nut will be tightened while the member 58 will be held against rotation, thereby causing axial movement of the member 58 to thus adjust the tensioning on the wire 40. A compression spring 72 surrounds the member 58 and has its lower end abutting against a flange or abutment surface 74 on the member 58 and its upper end bears against the nut 66. Thus, by rotating the member 68, the spring 72 may be adjustably compressed thereby varying the tension applied to the cutting wire 40.

As it will now be apparent, the wire 40 is tensioned between the fixed spring 52 at its lower end and the adjustable spring 72 at its upper end. By this arrangement, the wire can be moved downwardly by sliding the handle 60 to the lower end of the slot 38, into the dotted line position indicated at 76 in Figure 2. In this position, the wire will lay flat upon the top surface of the top wall 18 of the table and a cake or other article 22 to be sliced may be placed thereon and centered upon the table. When the wire is now moved upwardly, as shown in dotted lines as at 78 in Figure 2, it will sever the article until when moved in its uppermost position as shown in full lines in Figure 2, a cut will be made through the center of the article. If it is desired to divide the article in half, the table 18, with the cutting wire in the vertical position shown in the full lines in Figure 2 may be rotated through 180° and again resiliently retained in adjusted position and the wire then moved downwardly in a reverse direction, thus completing the dividing of the cake along its diameter. Obviously, by rotating the table through selected angular intervals, corresponding to the circumferential spacing of the locking pockets 32, the cake or other article may be severed into segments of any desired size.

When it is desired to cover the cake or other article when left upon the table, as shown in dotted lines in Figure 2, or to store the device when not in use, a plastic or other suitable cover 80 of a hemispherical shape is employed. This cover has a rim which will surround and enclose the guide 34 with the lower edge of the rim seating upon the base, as shown clearly in Figure 2. At its upper portion, the dome is provided with an open neck 82 which is of sufficient size to slide down upon and snugly embrace the handle 60 and enclose the same, and establish a retainer to hold the handle in its vertical position.

From the foregoing, the construction and operation of the device will be readily understood and further ex-

planation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A slicer for pies and cakes comprising a base having a raised table support, a table having a depending skirt and a raised central portion rotatably mounted upon said table support and adapted to receive an object to be sliced, an arcuate bridge mounted on said base and overlying said table, a cutting wire, means for resiliently mounting one end of said wire upon said base, a handle attached to the other end of said wire and slidably mounted upon said bridge whereby said wire may be moved arcuately in vertical planes from horizontal to vertical positions for slicing articles carried by said table, said table skirt and table support having index means for securing said table in rotationally adjusted position upon said support.
2. A slicer for pies and cakes comprising a base having a table support, a table rotatably mounted upon said table support and adapted to receive an object to be sliced, an arcuate bridge mounted on said base and overlying said table, a cutting wire, means for mounting one end of said wire upon said base, a handle attached to the other end of said wire and slidably mounted upon said bridge whereby said wire may be moved arcuately in vertical planes from horizontal to vertical positions for slicing articles carried by said table, a resilient means yieldingly urging said handle away from said mounting means whereby to tension said wire, means on said handle for varying the tension of said resilient means on said wire.
3. A slicer for pies and cakes comprising a base having a table support, a table rotatably mounted upon said table support and adapted to receive an object to be sliced, an arcuate bridge mounted on said base and overlying said table, a cutting wire, means for mounting one end of said wire upon said base, a handle attached to the other end of said wire and slidably mounted upon said bridge whereby said wire may be moved arcuately in vertical planes from horizontal to vertical positions for slicing articles carried by said table, said mounting means having a resilient connection between said wire and base, a resilient means yieldingly urging said handle away from said mounting means whereby to tension said wire, means on said handle for varying the tension of said resilient means on said wire.
